UNITED STATES PATENT OFFICE

158,097

COMBINED CLOCKCASE AND CIGARETTE LIGHTER

Samuel J. Kaufman, New York, N. Y.

Application September 7, 1948, Serial No. 148,498

Term of patent 14 years

(Cl. D42—7)

To all whom it may concern:

Be it known that I, Samuel J. Kaufman, a citizen of the United States, residing at New York city, in the county and State of New York, have invented a new, original, and ornamental Design for a Combined Clock Case and Cigarette Lighter, of which the following is a specification; reference being had to the accompanying drawing, forming a part thereof.

Fig. 1 is a front elevational view of a combined clock case and cigarette lighter, showing my new design.

Fig. 2 is a top plan view thereof.

Fig. 3 is a rear elevational view thereof, with the lighter cover in operative position.

The dominant feature of the design resides in the portions shown in full lines.

I claim:

The ornamental design for a combined clock-case and cigarette lighter, substantially as shown and described.

SAMUEL J. KAUFMAN.
